SHEET STACKING MACHINE

Lawrence S. Brown, Massapequa, N. Y., assignor
to The Sperry Corporation, a corporation of
Delaware

Application April 19, 1949, Serial No. 88,441

4 Claims. (Cl. 271—79)

1

This invention relates to a machine for stacking large sheets of flexible material, such as paper, which are delivered thereto at high speed, as from a high speed rotary printer.

It has for an object to provide a machine of the above type which is capable of progressively stopping the forward motion of the sheets and laying them horizontally on a stack in smooth un-wrinkled condition.

Another object is to provide a machine of the above type which is capable of being adjusted to operate with sheets of various sizes and at various delivery speeds.

Another object is to provide, in a machine of the above type, controlled ejector means for ejecting a single sheet for purposes of inspection.

A more specific object is to provide a stacking device which is capable of operating with high speed rotary presses.

Various other objects and advantages will be apparent as the nature of the invention is more fully disclosed.

The novel features which are characteristic of this invention will be better understood by referring to the following description, taken in connection with the accompanying drawings in which a specific embodiment thereof has been set forth for purposes of illustration.

In the drawings:

Fig. 1 is a horizontal section of a stacking machine embodying the present invention, taken on the line 1—1 of Fig. 2;

Fig. 2 is a vertical longitudinal section through the machine, taken on the line 2—2 of Fig. 1;

Fig. 3 is a broken horizontal section similar to Fig. 1 but on a larger scale, showing the operator's side of the machine;

Fig. 4 is a vertical section of the timing adjustment mechanism, taken on the line 4—4 of Fig. 3;

Fig. 5 is a horizontal section similar to Fig. 3 showing the drive side of the machine;

Fig. 6 is a vertical section similar to Fig. 2 but on an enlarged scale, showing the sheet receiving end of the machine;

Fig. 7 is a vertical section similar to Fig. 6 showing the stacking end of the machine;

Fig. 8 is a vertical section similar to Fig. 6 showing the parts in a different position with the lower end of the ramp broken away;

Fig. 9 is a detail view showing the lower end of the ramp;

Fig. 10 is a broken horizontal section showing the sheet conveyor and gripper bars;

Fig. 11 is an enlarged section taken on the line 11—11 of Fig. 3 illustrating the timing adjustment mechanism;

2

Fig. 12 is a section similar to Fig. 11 showing the parts in a different position;

Fig. 13 is a section taken on the line 13—13 of Fig. 12 illustrating a detail of the ejector mechanism;

Fig. 14 is a section taken on the line 14—14 of Fig. 12 showing the timing cam;

Figs. 15 and 16 are sections taken on the lines 15—15 and 16—16, respectively, of Fig. 11;

Fig. 17 is a vertical section through the transfer chain taken on the line 17—17 of Fig. 10 but on a larger scale;

Figs. 18, 19 and 20 are sections taken on the lines 18—18, 19—19 and 20—20, respectively, of Fig. 17 showing the construction of the gripper bars;

Fig. 21 is a detail section taken on the line 21—21 of Fig. 22;

Fig. 22 is a section taken on the line 22—22 of Fig. 21;

Fig. 23 is a section taken on the line 23—23 of Fig. 21;

Fig. 24 is a horizontal section taken on the line 24—24 of Fig. 22;

Fig. 25 is a section similar to Fig. 22 showing the parts in a different position;

Fig. 26 is a section similar to Fig. 23 showing the parts in a different position;

Fig. 27 is a diagrammatic view of the drive mechanism for the transfer and conveyor chains;

Fig. 28 is a section taken on the line 28—28 of Fig. 27;

Fig. 29 is a section taken on the line 29—29 of Fig. 27;

Fig. 30 is a detail sectional view of the drive mechanism;

Figs. 31 and 32 are detail perspective views showing parts of the transfer mechanism.

Referring first to Figs. 1 and 2, a web 35 is delivered at high speed from a machine such as a rotary printer over a delivery roll 36, between a pair of guide rolls 37, and around an idler roll 38, thence around drive roll 39 to a cutting station comprising a stationary knife 40 and a rotary knife 41 mounted on a rotor 42. The rotation of the rotor 42 is timed to cut the web 35 into sheets 34 of the desired length.

From the cutting station the sheets 34 are fed to a sheet conveyor shown as a set of belts 43 travelling at a speed higher than that of the web and passing around rollers 44 to 48.

The belts 43 deliver the leading edge of each of the sheets 34 to a gripper bar 50 which at that time is in a position to grip said edge and is travelling at a speed somewhat less than the forward speed of the sheet. The gripper bars as they

advance from right to left as seen in Figs. 1 and 2 are decelerated by the mechanism to be described until they are brought to rest at a point over the left hand side of the stack 51 whereupon the gripper bars are opened to release the cut sheets 34 onto the stack. The gripper bars 50 travel in an endless circuit and after releasing the sheets are accelerated until they are brought to their proper speed for gripping the next sheet.

An air blast 52 from a row of nozzles 53 is directed against the upper surface of the sheet 34 after the sheet has been gripped by a gripper bar 50 so as to cause the sheet to be removed rapidly from the belts 43 and to fall onto the previous sheet on a ramp 55. Due to the fact that the gripper bars 50 are moving at a slower speed than the belts 43 the sheet immediately forms a catenary loop as it is gripped by the bars 50. The air blast 52 is directed onto this loop and serves to pull the trailing end of the sheet from the conveyor belts 43. A second air blast 54 from a row of nozzles 56 is directed against the lower end of the sheet to cause the same to lie flat against the ramp 55. As the successive sheets are gripped by gripper bars which are progressively displaced, the sheets lie in shingled formation, the trailing edge of the last sheet extending below the edge of the preceding sheet and lying against a vacuum pad 57 which is carried by the ramp 55 and which assists in holding the lower edge of the sheet flat against the ramp.

The stack 51 rests on a platform 60 which is progressively lowered by chains 61 as the stack increases in thickness, so that the top of the stack remains at substantially the same elevation. After the stack has reached a predetermined thickness it may be removed from the machine and a new platform 60 inserted by means not shown herein.

Referring to Figs. 2, 3, 5, 6, 8 and 9, the ramp 55 is shown as comprising a frame 65 hinged at the top over a roller 66 and carrying across bars 67, 68 and 69. The cross bar 67 is fixed to the frame 65 and carries a plurality of spaced vertical rods 70 on which the sheets rest. The cross bar 68 is adjustable along the frame 65 and may be secured in adjusted position by bolts 71. The cross bar 69 carries a plurality of spaced vertical rods 72.

The cross bar 69 is mounted for vertical adjustment on a slide 73 which is slidably mounted on the frame 65 and is secured in adjusted position by bolts 74. The slide 73 also carries the vacuum box 57 having a perforated top plate 75 over which the lower edge of the cut sheets fall. A plurality of spaced vertical rods 76 are mounted on the cross bar 69. A plurality of similar spaced bars 77 are mounted on a cross bar 78 attached to the slide 73. The central rods are rigidly mounted on the cross bars as by welding. The rods at the two sides of the ramp, however, are made adjustable so that the ramp may be adjusted to various widths of web. For this purpose the various rods at the two sides of the ramp are mounted on U-shaped brackets 80, 81 and 82 (Figs. 8 and 9) which are, respectively, slidable along the cross bars 67, 68 and 69 and may be set in adjusted position by means of set screws. The inclination of the ramp may be adjusted by means of a bar 85 attached to the frame 65 and sliding in a strap 86 which is clamped to a stationary bracket 87 by means of a bolt 88.

A vacuum pad 89 is positioned to engage the trailing end of the bottom sheet as it leaves the

ramp 55 to disengage the sheet for release onto the stack 51.

Referring now to Figs. 17 to 20, each gripper bar 50 comprises a pair of end plates 100 carrying rollers 101 which travel in tracks 102 attached to the frame of the machine and forming an endless path. A transverse tube 103 is attached to the end plates 100. This tube carries an elongated stationary jaw member 104 at its lower side and at its top carries a toothed bar 105.

Movable jaw members 106 are mounted on brackets 107 which are journalled to rotate about a transverse tube 108 which is also secured to the end plates 100. The brackets 107 carry arms 109 having a plurality of spaced notches 110 on their under sides to receive pins 115 to which are attached springs 111. The notches 110 permit adjustment of the spring tension.

Brackets 112 are also journalled about the tube 108 and have at their upper ends pawls 113 which are adapted to engage the teeth in the bar 105. The upper ends of the springs 111 are attached to pins 114 on the upper ends of the brackets 112. The brackets 107 and 112 are slidable along the tube 108 for purposes of adjustment in accordance with the width of the sheet to be gripped, and the engagement of the upper ends 113 of the brackets 112 with the teeth in the bar 105 secures the same in adjusted position.

30 A shaft 120 is journalled in the end plates 100 and extends through holes 121 in the brackets 112 which have sufficient clearance with the shaft 120 to permit the necessary pivotal movement of the brackets 112 about the tube 108.

35 The shaft 120 carries pawls 122 which engage rollers 125 carried by the arms 109 and serve to depress the arms 109 when the shaft 120 is rotated into the position shown in Fig. 19, thereby opening the movable jaw members 106 against tension of the springs 111. The shaft 120 is actuated by rollers 123 carried on arms 124 attached to the shaft 120.

40 As shown in Fig. 8, when the gripper bar 50 approaches its gripping station in its path around the circular portion 102a of the track 102, the roller 123 engages a stationary cam 128 which depresses the roller as it advances in a clockwise direction around the cam 128 so that the gripper jaws 106 are opened before the gripper bar reaches its lower position. The roller 123 then rides over the surface of an adjustable cam 130 which retains the jaws in open position until the roller reaches the end of the cam 130 at which point the roller is released and the jaws are closed by the springs 111.

45 As shown in Figs. 12 and 14, the cam 130 is in the form of a stepped cylinder which is mounted on a shaft 131 for rotation by a worm 132 and worm gear 133 from a transverse shaft 134 which extends across the machine and as shown in Fig. 3 and is provided at its end with an actuating arm 136 having a handle 137. The arm 136 may be latched in various positions of adjustment by means of a spring pin 138 engaging holes in a plate 139 (Fig. 4). A similar adjustable cam 130 is mounted at each side of the machine for actuating the rollers 123 on the two end plates 100 and are adjusted in unison by the shaft 134. The purpose of the adjustable cams 130 is to adjust the gripping position of the gripper bars 50 in accordance with the size of the sheet being stacked. The transverse positions of the various movable jaws 106 is also adjusted in accordance with the width of the sheet 34 and they are so disposed as to pass between the various conveyor

belts 43 (Figs. 1 and 10). As indicated in Fig. 10, the conveyor belt roller pulleys 44 are adjustably mounted on a shaft 145 which, as shown in Fig. 8, is mounted on a sliding bracket 150 having a rack 151 adjusted by means of a gear 152 for varying the position of the discharge ends of the belts 43 as desired.

Referring to Fig. 6, the sheet 34 is fed on the belts 43 under a stationary guide plate 155. The plate 155 is provided over certain of the belts 43 with a pair of holes in which balls 156 rest. These balls are held in a cage 157 and are adapted to ride on the sheets 34 being fed and to hold the same in contact with the belts 43.

In order to eject a sheet for purposes of inspection, a rock lever 160 is provided at each side of the machine (Figs. 11 to 16) and is pivoted about a shaft 161 extending across the machine. Each lever 160 is provided with a lower (cam) surface 162 to engage the rollers 123 of the gripper bars 50. When the surface 162 is in raised position as shown in Fig. 11, there is sufficient clearance to allow the rollers 123 to remain in their gripping positions. When the surface 162 is tilted downwardly, however, as shown in Fig. 12, it engages the rollers 123 and depresses the same to release the clamping jaws 106 as the gripper bars 50 progress from right to left as seen in Figs. 11 and 12.

The lever 160 is actuated by a link 164 which is secured at its free end to a block 165 and is normally held in its right-hand position as seen in Figs. 11 and 12 by a spring 166. A transverse shaft 167 extends across the machine through elongated slots in the links 164 and carries cams 168 which are adapted to engage the blocks 165 when the shaft 167 is rotated in either direction and thereby shift the blocks 165 and links 164 to the left. An actuating handle 170 may be provided to actuate the shaft 167.

In order to cause the machine to eject only a single sheet a latch is provided in the form of a member 171 pivoted at 172 to the lever 160 and adapted when the lever is depressed to engage a plate 173 carried on a fixed bracket 174. A spring 175 is positioned to hold the member 171 in latched position. The member 171 also carries a release pawl 177 which is adapted to be engaged by the roller 123 as the roller passes thereunder, so that the roller elevates the pawl about the pivot 172 and releases the latch 171 from beneath the plate 173, thereby allowing the spring 166 to return the parts to their original positions so that the roller 123 on the following gripper bar is not actuated. When the roller 123 is actuated by the surface 162 to open the clamping jaws 106 the sheet of paper which is held by the clamping jaws is released and falls onto the floor so that it can be inspected without stopping the machine.

The gripper bars 50 are fed along the machine by means of a transfer chain 185 (Figs. 1 and 3) on each side of the machine which passes over sprockets 186 and 187, and a conveyor chain 188 on each side of the machine which passes over wheels 189 and 190 (Fig. 1). The transfer and conveyor sprockets 186 and 189 are mounted on shafts 191 and 192, respectively, which are driven by means to be described. The drive for the chains 185 and 188 is illustrated in Fig. 27 as comprising a drive shaft 195 which is driven at a constant speed by a source of power not shown. The shaft 195 carries a gear 196 meshing with a gear 197 carried on a shaft 198. The shaft 198 carries a gear 199 meshing with a gear 75

200 on a shaft 201 carrying an arm 202 in which a pin 203 is journaled.

The pin 203 carries a gear 204 to which is attached an arm 205 carrying a roller 206 displaced from the axis of the pin 203 the same distance as the displacement of the axis of the pin 203 from the axis of the shaft 201. The gear 204 meshes with an internal stationary gear 207 to form an epicyclic train which is so designed that, as the gear 204 is driven around the gear 207, the roller 206 oscillates in a straight line in a direction normal to the plane of the paper as seen in Fig. 27 and with a linear harmonic motion.

The roller 206 engages a slot 210 in the forked end of a lever 212 which is attached to a shaft 213 and thus serves to rock the shaft 213 with oscillating motion which is very nearly rotary harmonic.

The shaft 213 carries a segment gear 214 (Fig. 28) meshing with a segment gear 215 attached to a shaft 216 and so arranged that the shafts 213 and 216 operate in opposite directions and by an amount determined by the relative radii of the segment gears 214 and 215. The segment gear 214 also meshes with a segment gear 217 carried by a shaft 220 which is connected by segment gears 221, 222 to oscillate a shaft 223. The shaft 223 carries a segment gear 224 meshing with a segment gear 225 carried by a gear 226 forming one side of a differential 227. The shaft 216 also carries a segment gear 230 meshing with a segment gear 231 on a shaft 232 carrying a segment gear 233 meshing with a similar gear 234 carried by a gear 235 forming one side of a differential 236. The connections are such that the input gears 226 and 235 are oscillated in synchronism and in the same direction but by different amounts which may be adjusted by suitable selection of the segment gears 230 and 231.

The shaft 198 carries at its far end a gear 238 meshing with a gear 239 carried by a gear 240 forming the opposite side of the differential 236. A gear 241 is driven by the gear 239 and is attached to a gear 242 forming the second side of the differential 227. Hence the gears 240 and 242 of the two differentials are rotated in opposite directions and by different speeds which depend upon the ratios of the gears 238, 239 and 241.

The spider 245 of the differential 236 is attached to a shaft 246 carrying a gear 247 meshing with a gear 248 carried by a shaft 249 which, through beveled gears 250 and 251, drives the shaft 191. The gears 247 and 248 may be changed for varying the drive ratio. The spider 253 of the differential 227 is attached to a shaft 254 which, through beveled gears 255 and 256, drives the shaft 192. The shafts 191 and 192 are thus driven in the same direction, but at different speeds each of which varies with the timed motion introduced by the oscillation of the gears 235 and 226, and the average rates of which differ in accordance with the various gear ratios. The gears are so selected that the maximum speed of the transfer chain 185 is somewhat less than the rate of feed of the paper sheet 34, preferably between 60% and 85% of the linear rate of feed of such sheet, and the minimum speed of the transfer chain 185 is equal to the maximum speed of the conveyor chain 188. The minimum speed of the conveyor chain 188 is zero. The duration of the time cycle during which the chains go through the above men-

tioned variations is equal to the time interval between delivery of successive sheets to the gripper bars.

The mechanism for selectively connecting the gripper bars 50 to be driven by the two sets of chains is illustrated in Figs. 21 to 26. Referring to these figures, each end plate 100 carries an arm 260 having a pair of pins 261 and 262 on which two pairs of clamping jaws 263, 264 and 265, 266 are mounted. The jaws 263 and 264 are interconnected by a pin 267 and slot 268 to cause the jaws 263 and 264 when elevated to the positions shown in Fig. 23 to engage a feed pin 269 carried by the conveyor chain 188, and when retracted in the position shown in Fig. 26 to release such pin. Similarly the clamping jaws 265 and 266 are interconnected by a pin 271 and slot 272 to cause the jaws to operate in unison so that when elevated as shown in Fig. 25 they engage a feed pin 273 carried by the transfer chain 185 (Fig. 21) and when retracted as shown in Fig. 22 they are released from said pin.

For selectively actuating the two sets of clamping jaws a cam plate 280 is provided which is pivoted about a pin 281 carried by the bracket 260 and carries a pair of lugs 282 and 283 (Fig. 31) which are adapted to engage shoulders 284 and 285 on jaws 263 and 265, respectively, for retracting one of said jaws and advancing the other as the cam plate 280 is shifted about its axis. The cam plate is also provided with surfaces 286 and 287 which contact the respective shoulders 284 and 285 for locking either the jaws 263 and 264 or the jaws 265 and 266 in elevated positions. The shoulders 288 and 289 on the plate 280 form stops to limit the movement thereof.

In order to prevent the plate 280 from moving when not actuated by external means a pointed cam surface 292 is provided engaging a roller 293 mounted on an arm 294 which is pivoted to a pin 295 on the bracket 260 and is held inwardly by a spring 296. The roller 293, riding over the pointed cam surface 292, locks the plate 280 in either the position shown in Figs. 22 and 23 or the position shown in Figs. 25 and 26. The connections are such that one set of jaws engages a feed pin before the other set of jaws has entirely released its feed pin so as to avoid possibility of entirely releasing the gripper bar from both chains during the shifting operation.

In order to shift the cam plate 280 from one position to the other, the plate is provided with an arm 298 carrying a roller 299 which engages suitable stationary cam surfaces at the appropriate places along the path of movement of the gripper bars. As shown in Fig. 6, the roller 299 engages a stationary cam 300 which is adapted to force the roller downwardly for shifting the clamping jaws from the transfer chain to the conveyor chain at that point and engages a stationary cam 301 for shifting the clamping jaws from the conveyor chain to the transfer chain. These points are so selected that at both points the feed pins of the two chains are in alignment and traveling at the same speed.

An adjustable cam 305 (Fig. 7) controls the release of the gripping jaws 100. This cam 305 is mounted on a slide 306 having a rack 307 engaged by a gear 308 mounted on a shaft 309 for purposes of adjusting the point of release of the sheets by the gripper bars. A handle 310 is provided (Figs. 3 and 17) for actuating the shaft 309. A spring pin 311 is carried in the hub 312 of the handle 310 for latching the handle in selected positions.

The operation of this device may be summarized by reference to Fig. 2. The web 35 which is received at a high speed is cut into the desired lengths by the rotating knife 41. The leading edge of each sheet 34 into which the web is cut is fed by the belts 43 into the open jaws of a gripper bar 50 which is timed to receive the same and at that instant is being advanced at nearly maximum speed by the transfer chain 185. The gripping jaws then close to grip the forward end of the sheet and the gripper bar immediately begins to slow down due to the oscillating component of the rate of speed of the transfer chain. When this occurs the sheet 34 forms a loop due to the difference in speed between the gripper bar and the belts 43 and is blown downwardly by the air jet 52 to form a shingled stack on the ramp 55. As the gripper bar is fed along by the transfer chain 185 and reaches the point of minimum speed of the transfer chain it is shifted to the conveyor chain 188 which at that time is traveling at its maximum speed. The gripper bar is thereafter fed along by the conveyor chain at varying rates through several cycles until it momentarily becomes stationary at the point of delivery where the sheet has been drawn completely over the stack 51. The gripping jaws are then released to drop the stationary sheet. The gripper then continues its travel on the conveyor chain until it is again shifted to the transfer chain which occurs after one or more cycles of travel and at an instant when the conveyor chain is traveling at its maximum speed. Thereafter the transfer bar is advanced through one or more cycles by the transfer chain until it is again brought into sheet receiving position.

It is to be noted that each sheet is separately laid on the stack 51 and is separately brought down from maximum speed to a condition of rest before it is released onto the stack. Hence the device may be used for stacking very thin sheets of material such as tissue paper weight which if not restrained would tend to crumple if suddenly brought to rest from the high speed of the traveling web.

Obviously if the rate of speed of the web is not too great the gripper bars may be brought from maximum speed to rest or nearly so by means of a single chain in which event the transfer mechanism may be omitted. In the event of very high speeds, however, it is impractical to reduce the speed of advance of the gripper bars from maximum speed to a condition of rest during the small interval of time allowed between the presentation of successive sheets to the stacker mechanism.

Various changes and modifications may be made as will be apparent to a person skilled in the art.

What is claimed is:

1. A machine for stacking sheets of flexible material fed thereto in a rapidly advancing procession, comprising a plurality of gripping members, means advancing said gripping members in an endless path in succession from a sheet receiving station through a sheet releasing station back to the sheet receiving station, said advancing means comprising a pair of conveyors operating in line in the same direction, means driving each of said conveyors at a variable rate which varies cyclically between a maximum and a minimum rate of speed, the maximum rate of the first conveyor being somewhat less than the rate of advance of said procession, the minimum rate of said first conveyor being equal to the

maximum rate of said second conveyor, the minimum rate of said second conveyor being substantially zero speed, means on said first conveyor to advance said gripping members from said gripping station to an intermediate point between said gripping station and said releasing station, means between the gripping station and the intermediate point for successively deflecting the trailing portions of the gripped sheets from the path of the succeeding sheets, means at said intermediate point to transfer said gripping members from said first conveyor to said second conveyor, means located at the point of minimum speed of said second conveyor to cause said gripping members to release said sheets and means in the said return path of said gripping members to re-transfer the same to said first conveyor.

2. A stacking machine as defined in claim 1 in which the deflecting means comprise blower means located at a point beyond said gripping station and arranged to remove the trailing ends of said sheets from the path of the succeeding sheets, whereby said sheets are caused to hang downwardly from said gripping members as they are advanced thereby.

3. In a stacking machine, as set forth in claim 1, an inclined ramp positioned beneath the path of travel of said gripping members between said gripping station and said releasing station, means withdrawing the trailing ends of said sheets from the path of succeeding sheets after the sheets have been gripped by said gripping members and causing said sheets to fall downwardly upon said inclined ramp in shingled formation, whereby said sheets are pulled upwardly over said ramp by said gripping members as they advance to said discharge station, suction means disposed on said ramp to cause

the trailing ends of said sheets to lie flat against said ramp.

4. A stacking machine as set forth in claim 1 in which each of the gripping members comprises a bar disposed transverse to the direction of movement of the conveyors and carrying a plurality of sheet clamping jaws, and has means associated with the bars for gripping both conveyors, and there are cam means operative upon the gripping means and disposed in their paths to cause the said means at one point to grip the first conveyor and simultaneously to release the grip on the second conveyor, then at a succeeding point to release the grip on the first conveyor and simultaneously grip the second conveyor and then at the said one point again to grip the first conveyor.
